(57) CLAIM

The ornamental design for a glass container for food, as shown and described.

DESCRIPTION

FIG. 1 is a front elevation view of a glass for food containment showing my new design;

FIG. 2 is a front perspective view thereof;

FIG. 3 is a side perspective view thereof;

FIG. 4 is a side perspective view thereof; and,

FIG. 5 is a side view thereof.

In each Figure, all surfaces not shown form no part of the claimed design.

FIGS. 1-5 show an embodiment of the a glass container for food. In this embodiment, the basic form of the jar is an arched rectangle, which increases in width from the bottom. The lid is circular. The two narrow sides are straight until they reach the shoulder section, whereas the broad front and rear have a slight outward curve until they reach the shoulder part. The broad front and rear end in a circular arch pointing upwards. The lid can be of any color.

All sides not shown form no part of the claimed design.
